MEANS FOR UNITING SHEETS OR PLATES.

1,191,835.

Specification of Letters Patent. Patented July 18, 1916.

Application filed July 3, 1912. Serial No. 707,544.

To all whom it may concern:

Be it known that I, EDWARD W. SALMON, Jr., a citizen of the United States, residing at Baltimore, in the State of Maryland, have invented certain new and useful Improvements in Means for Uniting Sheets or Plates, of which the following is a specification.

This invention relates to a machine for uniting metal sheets or plates.

It is common practice in this art for milling establishments to furnish jobbers and others with metal sheets or plates which the jobbers or others have to unite or connect together when it is desired to use the same for roofing or other purposes. The jobbers and others frequently unite these sheets or plates by first edging one end of the same by a hand operated machine. The sheet or plate is then reversed by hand to edge the opposite end of the same. After a number of sheets or plates have been edged in this way the operator overlaps one end of one sheet or plate with an end of another and then feeds the overlapped sheets or plates by hand between means for seaming their overlapped ends. This single lock seam is usually soldered to prevent leakage at the joint and it is sometimes painted to protect the metal. If it is desired to form a double lock seam to obviate soldering of the single seam and to prevent leakage the operator has to take the plates to a separate machine for forming double lock seam ends, and subsequently slide the edged ends together and then the double lock seam is effected by hand operated devices. These steps require separate machines and considerable time, labor and expense which my improved machine 40 is designed to obviate.

One object of the present invention is to provide a machine operable automatically to shear and edge sheets of material and subsequently unite the sheets together and wind the same into a marketable roll.

Another object resides in the provision of an automatically operating machine embodying among other characteristics means for edging, single and double lock seaming and winding the material thus united into a marketable roll by a substantially straight feed of the material in a substantially horizontal plane from the edging means to the winding means.

Another object is to provide in a machine

for operating upon sheet roofing material composed of a plurality of connected sheets or plates, means whereby the material may be fed through the machine, together with means for bending the sheets or plates at the point of overlapping during the feed of the material through the machine.

Another object resides in the provision of a machine of the nature stated, embodying among other characteristics, means constructed and arranged to indicate when a predetermined number of sheets have been connected together and to automatically throw the machine out of operation when a predetermined number of sheets have been 70 connected.

Another object is to provide an automatically operating machine embodying means for single lock seaming separate sheets or plates together and subsequently forming 75 the single lock seams into double lock seams calculated to render the joint water tight without the use of solder.

Another object resides in the provision of an automatically operating machine for edging the ends of sheets and transferring them to a table where they are disposed in overlapping relation and fed in their overlapping relation to means for single lock seaming the overlapped ends together and subsequently taken to means adapted to act upon the single locked seamed joint to form the single locked seamed joint into a double lock seam to prevent leakage at the joint with the means for feeding the material through the machine also performing the function of winding the locked sheets into a marketable roll.

A still further object is to provide a machine for operating upon sheets of material for the purpose of uniting them together with means operable automatically and operatively connected to the uniting means for shearing and edging the sheets prior to uniting them together, there being means operatively connected to the uniting means for winding the united sheets into a roll ready for the market.

A still further object is to provide an automatically operating machine embodying among other characteristics means whereby a plurality of sheets may be sheared and edged and united together and rolled into a bundle ready for the market with the machine so constructed that it may be readily 110

and expeditiously adjusted for operation upon sheets of various widths and lengths.

It is still further designed to provide an automatically operating machine whereby 5 metallic or other sheets of material may be united together after they have been sheared and edged by mechanism operatively connected to the uniting means with the machine also provided with mechanism whereby 10 the sheets may be fed through the machine and wound into a roll ready for the market, there being means constructed and arranged to indicate when the predetermined number of sheets have been united to thereby automatically 15 throw parts of the machine out of operation to prevent uniting a single sheet more than the predetermined number to be wound into a marketable roll.

With the above and other objects in view, 20 the present invention consists in the combination and arrangement of parts hereinafter more fully described, illustrated in the accompanying drawings and particularly pointed out in the appended claims, it being 25 understood that changes may be made in the form, proportion, size and minor details without departing from the spirit or sacrificing any of the advantages of the invention.

30 In the drawings:—Figure 1 is a side elevation partly in vertical section. Fig. 2 is a vertical longitudinal section through the edging mechanism illustrating on a large scale the means for shearing and edging the sheets. 35 Fig. 3 is a plan view of one of the clamping members partly broken away to show the location of the corresponding shearing blade. Fig. 4 is a top plan view of the invention. Fig. 5 is a vertical longitudinal 40 sectional view through the mechanism for forming single and double lock seams. Fig. 45 6 is a rear elevation, partly in section and with parts removed. Fig. 7 is an elevation of the reel. Fig. 8 is an edge view of one 50 of the sheets which has been sheared and edged. Fig. 9 is a fragmentary edge view of two sheets having their edged ends overlapped. Fig. 10 is a similar view illustrating the overlapped ends of the two sheets 55 formed into a single lock seam. Fig. 11 is a similar fragmentary view illustrating the material at the single lock seam doubled prior to converting the single lock seam into a double lock seam. Fig. 12 is a similar 60 fragmentary view illustrating the condition of two adjacent sheets flattened out subsequently to the doubling of the material to provide a double lock seam. Fig. 13 is an enlarged detail view illustrating the mechanism for throwing the single and double 65 lock seaming devices out of operation and for indicating the number of sheets connected together and being fed through the machine.

65 In carrying out my invention, I employ

preferably two separate frames A and B. The frame A preferably includes side sills 10 and 11 connected together by means of suitable cross pieces 12 and 13 and mounted upon suitable legs 14. The frame B preferably includes side sills 15 and 16 and an intermediate sill 17 with the sills connected or cast with the transverse cross-pieces 18, 19 and 20. This frame B is preferably supported by suitable legs 21 and the two frames 70 75 may be bolted or otherwise secured together as indicated at 22.

With the understanding that plates or sheets of varying lengths and widths may be operated upon in the use of my invention 80 and with the further understanding that milling establishments furnish jobbers with unconnected or separate sheets or plates, we will assume that the milling establishment has furnished a quantity of metal plates or 85 sheets and it is desired to unite them together and form them into a roll for the market to use for roofing or other purposes. These sheets or plates we will assume are twenty-eight inches in length or approximately so. Sometimes the ends have been properly "mill-squared", that is, the ends have been sheared at a direct right angle to the longitudinal edges of the sheets or plates. At an increased expense to jobbers the milling establishments will re-square the sheared ends of the sheets. As this necessitates an extra operation on the part of the milling establishment, and as hand operated machines are used for the purpose of re-squaring the ends of the sheet, the expense is obviously increased. Therefore, the jobber pays the milling establishment extra to re-square the ends of the sheets or himself re-squares the "mill-squared" ends through the 90 use of hand operated machines. The jobber is put either to additional expense or to considerable loss of time. If the ends of the sheets are not true, that is, properly squared, a proper joint cannot be made in uniting the 95 sheets together. To save additional expense and loss of time in re-squaring, I first provide the means for simultaneously shearing and providing each end of each plate with a hook or what is commonly termed an edge, although, 100 as intimated, I do not confine myself to shearing the ends of the sheets. To accomplish this simultaneous shearing and edging of the ends of each sheet, I mount in suitable standards 23 and 24 disposed on the frame A, spaced cam shafts 25 and 26, each having two or more spaced cams 27 and 28 thereon. Immediately over the cam shafts 25 and 26 I mount vertically movable clamping members 29 and 30 each of which carries an arm 31 at each end thereof whose outer ends are pivotally connected at 32 to the arms 33 of the standards 23 and 24. These clamping members coöperate with clamping members 34 and 35 fixedly mounted in the arms 34' 105 110 115 120 125 130

and 35' of the standards 23 and 24, respectively. Thus, the clamping members 34 and 35 remain stationary, while, by virtue of the pivotal arm connections 31 of the movable clamping members 29 and 30, the latter may be raised into coöperative relation with the clamping members 34 and 35 to clamp and hold the sheets or plates 36 to be sheared and edged. To effect the vertical movement of the movable clamping members 29 and 30 I have provided the aforesaid cam shafts 25 and 26 with the said cams 27 and 28 adapted to engage rollers 37 carried by the movable clamping members 29 and 30 so that as the 15 cam shafts are rocked the engagement of the cams 27 and 28 with the rollers 37 will effect the raising and lowering of the movable clamping members 29 and 30. I provide each of the cam shafts 25 and 26 with a 20 crank arm 38 and 39, respectively, to which I pivotally connect a link 40 with a pitman 41 secured to the pivotal connection 42 between the link 40 and the crank arm 39 so that upon operation of the pitman the cam 25 shafts are rocked. This pitman 41 may be operated in any suitable manner to effect oscillation or rocking of the cam shafts 25 and 26 so as to raise and lower the movable clamping members 29 and 30 in a manner 30 which should now be understood. I will later describe one means by which the pitman 41 may be operated and it will be the way it is preferably operated in carrying out the present invention. As the clamping 35 members 29 and 30 are raised into clamping coöperation with the fixed clamping members 34 and 35 to hold the sheet or plate 36 between them through the instrumentality of the cam mechanism and pitman connection hereinbefore described, there is set in 40 operation means for shearing and bending the opposite ends of the metal plate 36. This means consists of a shearing blade holding member 44 having an inclined face to which 45 face a shearing plate 45 is connected in any suitable manner and whose shearing edge is indicated at 46. Secured to the shearing blade holding member 44 are bearings 43 in which are journaled the short shafts 43 secured to the frame A. To one of the short shafts 43 is rigidly connected a crank arm 47 which has pivotal connection with a link 48 pivoted at 49 to another crank arm 50 fixedly secured to a shaft 51 to which latter 55 is fixedly secured a shearing blade holder 52 to the inclined face of which is secured in any suitable manner a shearing blade 53 having a shearing edge 54 so that upon reciprocation in any suitable manner of the pitman 55 of the aforesaid crank arm 47 and link 48 the shearing blade holders 44 and 52 with their blades are swung on their axes 43 and 51.

As seen in Fig. 1 the plate or sheet 36 is 55 positioned so that when it is clamped be-

tween the upper clamping members 34 and 35 and the lower clamping members 29 and 30 its ends project slightly beyond the same. By a movement in one direction of the pitman 55 the blade holder 44 is swung downwardly and as it swings downwardly the shearing edge 46 of blade 45 engages the metal sheet 36 evenly and bends it into engagement with the shearing edge 57 of the blade 58 fixedly secured in any suitable 70 manner to the movable clamping member 30. As this inner end of the sheet 36 is sheared the edge 46 of the blade 45 continues into the notch 59 and forces the sheared edge of the plate 36 against the face 60 of the movable clamping member 30 and thereby provides the inner end of the sheet or plate with a hook or edge 61 which is thereby disposed at an angle to the body of the plate. As the inner end of the plate 36 is thus sheared and bent, the outer end of the plate is likewise sheared and bent only that instead of bending the outer end downwardly during the shearing and bending process, the outer end is directed upwardly to form the hook 85 or edge 62 (Fig. 8). For instance, when the swinging blade 45 is swung downwardly the link connection 48 between the crank arms 47 and 50 causes the blade holder 52 to swing upwardly and in its upward swing the shearing edge 54 of the shearing blade 53 90 engages the outer end of the sheet 36 and bends it around so that when the shearing edge 54 reaches the cutting edge 63 of the shearing blade 64 secured in any suitable 95 manner to the fixed clamping member 34, the outer end of the sheet 36 is sheared evenly and the continued swinging movement of the shearing edge 54 of the blade 53 will force the sheared outer edge of the plate 100 past the shearing edge 63 of the blade 64 and into the notch 65 against the flat surface 66 on the fixed clamping member 34 and thereby provide the upwardly directed hook 105 end or edge 62 at the outer end of the 110 plate 36.

While I have illustrated herein my improved combined shearing and edging device in combination with means for carrying out other steps in the production of a 115 finished product and have intimated that the pitman connections 41 and 55 for operating the same may be controlled in any suitable manner, it might be noted that instead of operating the device automatically 120 by machinery as will be later described, these pitman connections 41 and 55 may have substituted for them means for manually effecting the aforesaid operations, or the pitman connections 41 and 55 may be connected up 125 with automatic mechanism other than that which will be later described.

After I have sheared and bent the ends of a plate 36 in the manner described, the plate 130 is transferred automatically from the shear-

ing and edging mechanism to a table 67 along one side of which may be placed a gage 68 to guide material through the machine. This table is of a width to accommodate sheet metal or plates of varying widths, say for instance twenty inch, twenty-six and one-half inch, twenty-eight inch, etc. This table 67 may be supported in part on the cross piece 18 of the frame B and on bracket arms 69' which may extend from the table or frame A or in any other suitable manner. To effect the transfer of the sheared and edged plates I provide means consisting of preferably a pair of chains 69 which are mounted over sprocket wheels 70 carried on the shafts 71 and 72 mounted in brackets 73 on the frame A, there being fingers 74 on the chains 69 and at predetermined times or immediately after the shearing and bending of the ends of the plate 36 these fingers 74 are adapted to engage the plate 36 and carry it on the chains 69 under the influence of operation of the latter in a manner presently explained, to the table 67 where there is already a plate 70 sheared and bent like the plate 36 in Fig. 8 so that the inner downwardly turned end 61 of the transferred plate 36 may overlap the upwardly turned end 62 of the plate 70 which is already on the table 67, as has been stated, and against the guide 67 ready for feed through the machine so that the hooked overlapping ends or edges 61 and 62 of the plates 36 and 70 may be fed in this relation in a manner to be presently explained through the machine for firmly uniting the overlapped ends 61 and 62 of the plates.

To operate the transferring mechanism I provide a counter shaft 75 journaled in any suitable manner in the frame A and which has on it sprocket wheels 76 adapted to engage between the runs of the chains 69 to operate the latter when the counter shaft 75 is rotated. Keyed to the inner end of the counter shaft 75 is a beveled pinion 76' adapted to mesh with a beveled gear 77 keyed to a shaft 79 provided with a worm gear 80 with which may mesh a worm 81 carried by the drive shaft 82 of any suitable motor 83. In this particular instance, the shaft 79 forms the main drive shaft of my improved machine and it is preferably journaled in any suitable manner in the table or frame B and transversely of the latter. However, it will be seen from the foregoing that in combination with the combined shearing and edging device I may provide the transferring device and drive or operate the latter by or from any suitable source. After shearing and edging the plates and transferring them from the shearing and edging device to the table and after abutting plates have their hooked ends overlapped, I operate upon the hooked overlapped ends to form a single and a double lock seam in

a manner which will be hereinafter described and in order to effect a feed of the overlapped and united plates through the machine I provide a winding reel 84 with which reel the hooked end 61 of the first plate 36 is connected so that as the plates which are interlocked with the first plate 36 and with the overlapping plates on the table 67 are pulled or drawn through the machine by said reel 84 having frictional drive connection with the main drive shaft.

To single and double lock the seams I provide on the frame B spaced pairs of uprights 85 and 86 each upright of each pair having a slot 87 in its upper end. In the front pair of standards 85 I mount upper and lower single lock seaming rollers 88 and 89 geared together by the intermeshing gears 90 and 91 and in the rear pair of uprights 86 I mount upper and lower double lock 85 seaming rollers 92 and 93, respectively, geared together by the gears 94, and 95, the lower rollers 89 and 93 being secured to shafts 96 and 97 respectively, journaled in the pairs of uprights 85 and 86 and driven by means of chains 98 and 99 operating over the sprocket wheels 100 and 101 on the main drive shaft 79 and over the sprocket wheels 102 and 103 on the shafts 96 and 97 of the lower rollers. The upper rollers 88 and 92 are secured to shafts 104 and 105, respectively, which are normally positioned on the lower ends of the slots 87 of the uprights 85 and 86. On the front and rear lower shafts 96 and 97 are pairs of levers 106 and 107 connected by suitable links 108. These levers have curved slots 109 in which said shafts 104 and 105 are located. The upper rollers 88 and 92 may be lifted away from co-operative relation with the lower rollers 89 and 93, respectively, by means of these levers 106 and 107, as will be explained.

To connect up the shearing and edging device hereinbefore described to the seaming mechanism, I provide the front upper 110 and lower roller shafts 104 and 96 with two cams 109 and 110, respectively each having a cam groove 111 therein in which may operate a roller 112 carried at the outer end of the pitmen 41 and 55 so that as the shafts 115 104 and 96 revolve said cams revolve and cause said pitmen to effect the aforesaid operations of the shearing and bending mechanism.

As the sheets or plates 36 and 70 which have been overlapped as shown in Fig. 9 are passed between the rollers 88 and 89 they are flattened out under the weight of the upper rollers 88 as indicated at 113 in Fig. 10 to provide a single lock seam, the material being drawn between the rollers 88 and 89 by the winding reel 84 as has been stated. When each single lock seam 113 reaches the dogs 114 and 115 the feed of the material is stopped momentarily. These 130

dogs 114 and 115 are fixedly secured to a shaft 116 which is journaled in hanger plates 117 and 118 connected to the upper shafts 104 and 105. Immediately upon the 5 single lock seam 113 engaging the dogs 114 and 115, mechanism is set into operation to double up the two plates at the point of formation of the single lock seam as indicated at 117' in Fig. 11. This doubling of 10 the interlocked plates at the single seam connection 113 may be effected in one way by the provision of male and female dies. The female die plate is indicated at 118' and is formed of hard steel and provides a 15 clamping member and is carried by the vertically movable bed 119 swingingly mounted on the shaft 96 by the arms 120 and provided on its under side with rollers 121 adapted to be engaged by cams 122 keyed to 20 the main drive shaft 79 to support the swinging bed. The female die plate is raised with the bed 119 through the instrumentality of these cams 122 as the main drive shaft rotates because of irregular surfaces 25 of the cams engaging the rollers 121, effecting an alternate raising and lowering of said bed. When the female die plate 118' is raised the sheets or plates resting on its upper surface and directly over the recess 123 in the die plate 118' are forced 30 against the fixed clamping member 124 so that the sheets or plates 36 and 70 are held firmly between the die plate 118' and clamp member 124. The clamping member 124 35 may be held fixedly by reason of hanger arms 125 and 126 secured to or formed with the aforesaid hanger plates 117 and 118 which are connected to the upper roller shafts 104 and 105 as has been stated. As 40 the clamping bed moves upwardly and forces the sheets or plates 36 and 70 into tight engagement with the clamping member 124 the single lock seam joint 113 is forced down into the recess 123 in the die 45 plate 118' and against the flat face 125 of the female die and caused to assume the condition indicated at 117' in Fig. 11 through the instrumentality of a male die 127 swingingly mounted above the female die plate. 50 One means for swingingly mounting this male die 127 is to mount stub shafts 128 in the ends of the male die member 127 and to journal these stub shafts 128 in the aforesaid hanger arms 125 and 126 with a pinion 55 129 keyed on one of the stub shafts 128 for mesh with the teeth 130 of a rack bar 131 provided with a slot 132 which embraces the shaft 96 of the forward lower roller 89 so that as the shaft 96 revolves under the influence of the chain connection 98 between the shaft 96 and the main drive shaft 79 the cam 134 on said shaft engages the roller 135 60 on the rack bar 131 and reciprocates the latter in the guide 136 and in one movement of its reciprocation causes rotation of the 65 pinion 129 which results in a forward swinging movement of the male die member 127 whose forward edge 137 forces the joint 113 into the recess 123 of the female die plate 118' and against the flat surface 125 of the 70 recess of the female die plate. As the male die 127 swings forwardly it engages the dogs 114 and 115 and moves them on their pivots with the result that the arm 138 connected at one end to the upper end of the 75 dog 115 and having its slotted end 139 embracing the shaft 104 to move toward the forward end of the machine. As the arm 138 moves forwardly of the machine, the cam 140 fixed on the upper roller shaft 104 presents its flat edge 141 to the roller 142 on the arm 138. When the curved edge 139 of the cam 140 rides over the said roller 142 it forces the arm 138 rearwardly of the machine and consequently throws the dogs 114 80 and 115 to their normal position. By this time the cams 122 and the main drive shaft have permitted the bed 119 and female die to lower and the rack bar 131 has been returned to its normal position by the cam 85 134 engaging the roller 133 at the outer end of the rack bar. The reel 84 now draws the connected sheets or plates through the double lock seaming rollers 92 and 93 with the weight of the roller 92 flattening out the 90 material doubled at the point 117 to form a double lock seam 126 (Fig. 12) and the foregoing operations continue until a predetermined number of united sheets or plates have been wound upon the reel 84. It 95 is customary to unite twenty-eight sheets or plates and wind them into a roll for transportation. I therefore provide means whereby when the twenty-eighth sheet or plate has been wound upon the reel 84 to 100 prevent the seaming of the twenty-ninth sheet or plate to the twenty-eighth one. 105

In order that the operator need not give particular attention to the number of sheets or plates joined together and bound upon the reel, I journal in the frame B a shaft 143 on which there are keyed spaced wheels 144 and 145 each having a tooth 146. On this same shaft 143 there is keyed a ratchet wheel 147 having twenty-eight teeth 148', 110 which are numbered from 1 to 28, as shown, and swingingly mounted on the shaft 143 adjacent the ratchet wheel 147 is a lever 148 whose outer end is formed to provide a squared shoulder 149 which is adapted to ride on a wheel 150 mounted on the main drive shaft 79. Pivotaly mounted on the outer end of said lever 148 is a pawl 151 which is adapted to ride over said teeth 148' 115 on said ratchet wheel 147. During each rotation of the main drive shaft 79 two plates are overlapped and single and double lock seamed together and taken upon the reel 84, and therefore, as the shouldered end 149 120 of the lever 148 falls into the notch 151' of 125 130

said wheel 150 as the joined plates are taken to the reel, the said pawl 151 is provided and connected to this lever 148 for the purpose of engaging a tooth on the ratchet wheel 147 to move the ratchet wheel one step when the shouldered end 149 of said lever 148 is lifted out of the notch 151. This step-by-step movement of the ratchet wheel 129 effects step-by-step movement of the aforesaid wheels 144 and 145, and finally, when twenty-eight plates have been joined together in the manner hereinbefore described, the teeth 146 of said wheels 144 and 145 have been brought into engagement with the teeth 152 projecting from the front pair of levers 106 which forces said front levers 106 to swing forwardly on the front lower roller shaft 96 causing the upper front roller shaft 104 to ride on the aforesaid curved slots 109 of the front levers 106 elevating or lifting the shaft of the front roller 88 vertically in the slots 87 of the front standards 85 away from the lower roller 89. As the rear levers 107 are connected to the front pair of levers 106 by the aforesaid links 108 and have the curved slots 109 embracing the rear upper roller shaft 105, the upper roller 92 is likewise lifted away from the lower roller 93. The result is that the upper rollers cannot lock the seam at the overlapping ends of the twenty-eighth and twenty-ninth plates and the edge or hook 61 of the twenty-ninth plate 36 may be engaged with the reel 84 to repeat the operation heretofore stated. Thus it will be seen that since the teeth 148' of the ratchet wheel 147 are provided with teeth numbered from one to 28 which co-operates step by step the pawl 151 carried by the arm 148 swingingly mounted on the shaft 143, that there is provided means whereby by reference to the ratchet wheel 147 and the position of the pawl 151 with relation to the respective numbered teeth 148' that the number of sheets double lock seamed may be readily determined and when the upper rollers are raised in the manner stated at the time when the overlapping ends of the twenty-seventh and twenty-eighth sheets have been double lock seamed, the clamping member 124 and also the swinging die 127 are lifted out of engagement with the material passing over the body 119 because of the fact that the clamping member 124 and also the swinging die 127 are suspended by the arms 125 and 126 from the aforesaid hanger plates 117 and 118 connected to the upper roller shafts 104 and 105, as has been stated. The lifting means raises the upper rollers immediately after the twenty-seventh double lock seam has passed the rollers 92 and 93 and prior to the entry of the overlapped loose connection into and between the rollers 87 and 88.

The lower rollers 89 and 93 have flanges 153 and 154 respectively at their outer ends

which are adapted to align with the aforesaid gage 68 on the table 67 to insure a straight feed of the material through the single and double seaming rollers and the reel 84 is provided with the aforesaid tension drive because of the aforesaid momentary stoppage in feed of material when converting the single lock seam into a double lock seam so as to permit backward or unwinding movement of the reel 84 because of the innermost plate 36 being drawn backwardly with the outermost plate 36 clamped firmly between the die plate 118 and clamping member 124 when doubling the material as shown at 117 in Fig. 11.

To provide the friction drive for the reel 84 I mount upon the main drive shaft 79 a pulley 155 over which operates a belt 156 held under tension by an idler pulley 157 and having connection with a pulley 158 on a shaft 159 journaled in the brackets 160 on the frame B. This shaft 159 has sprocket wheels 161 adjacent its ends over which operate chains 162 leading to sprocket wheels on the outer ends of stub shafts 163 and 164 journaled in brackets 165 secured to the frame B. These stub shafts 163 and 164 have slidably mounted on their inner ends disks 166 provided with a plurality of fingers 167 adapted to project loosely through coinciding apertures formed in their inner fixed disks 168 of the reel. These disks 168 are fixed on the inner ends of the shafts 163 and 164 while the disks 166 have sliding movement thereon. It is on these fingers 167 of the disks 166 that the material is wound and when the aforesaid twenty-eight sheets or plates have been interlocked as described and wound upon the reel it is simply necessary to throw the disks 166 outwardly which draws the fingers 167 outwardly through the apertures of the fixed disks 168 when the wound material is permitted to fall on and roll down the enclosed guide 169 and is conveyed thereby to any suitable place, it being the custom when the sheets have been wound into a roll to tie or place bands around the same for shipping purposes. Various forms of reels may be used for this purpose but the one just described is the type of reel preferred and any suitable means may be employed in connection with the reel 84 to discharge the wound or rolled sheets or strips therefrom. One means which may be employed is shown particularly in Fig. 7 wherein it will be seen that I secure to the disks 166 the collars 170 which are slideable on the stub shafts 163 and 164. These collars have grooves 171 in their peripheries in which grooves the forked ends of levers 172 are engaged. These levers 172 have their lower ends diverted inwardly as at 173 and at the joint between the inwardly directed portions 173 and the forked portions 172 of the levers 130

they are pivotally mounted as at 174, on the lugs or brackets 175, secured to the frame B. The inwardly projecting portions 173 of the levers 172 preferably overlap. To effect a release of the wound material from the reel I provide an operating lever 176 which is pivotally mounted on one of the pivots 174 of one of the levers 172 and which extends beyond one side of the machine as seen in Fig. 7. By downward movement on the outer end of the lever 176 by foot or hand or otherwise, the inner end 177 thereof presses upwardly on the inner ends of the inwardly directed portions 173 of the levers 170 and causes the collars 170 on the stub shafts 163 and 164 and also the disks 166 to which said collars are connected to move outwardly and in this outward movement draw the fingers 167 through the apertures in the disks 168 and release the roll of material therefrom as has been stated.

The machine heretofore described is particularly adaptable for operation on sheets or plates of say for instance twenty-eight inches in length and twenty inches in width and as the machine is equally applicable for performing the functions herein described upon material of greater length and with it may be noted that if the material be of greater width than twenty inches it is simply necessary to shift the standard 165 to the left in Fig. 7 to space the disks 166 and 168 farther from the opposite disks 166 and 168 according to the width of the material. When this adjustment is made the corresponding lever 172 is pivoted in either the apertures 177 or 178 according to the width of the material. This is the only change that need be made to effectively operate on material of greater width than twenty inches. Where the material is of a length greater than twenty-eight inches, and say for instance, ten feet in length, practically the only changes that need be made in the machine are to substitute a larger pulley than that indicated at 155 and to adjust the front standard 23 and the front shearing and edging devices the required distance from the inner standard 24 and the inner shearing and edging devices. Thus the speed of the reel may be readily increased or decreased through the instrumentality of various sized pulleys substituted for the one indicated at 155 in the accompanying drawings. Whether the material be of twenty-eight inch length or ten feet length and it is desired that the reels contain more or less than twenty-eight sheets it is simply necessary to change the ratchet wheel 147 and substitute therefor a ratchet wheel with the number of teeth corresponding to the number of sheets to be wound in the bundle or roll on the reel.

It is evident from the foregoing that a strip of material composed of a plurality

of sheets or plates which have been single lock seamed or otherwise connected together, may be readily fed into the machine and the single lock seam manipulated to convert the same into a double lock seam.

I thus provide an automatically operating machine designed for the purposes hereinbefore stated which has the advantage of operating upon the sheet material without destroying its condition or strength and without the use of solder. In the use of solder the soldering tool must necessarily have such heat as to provide for the effective application of the solder. The heat of the soldering implement has a more or less deteriorating effect upon the coating of metal used particularly for roofing purposes. The metal of this character is usually coated with lead and tin and the application of a heated implement thereto causes melting of the coating. The melted coating is drawn away from the base material, that is, the iron body of the sheets, with the result that the base material or iron is exposed leaving the iron subject to practically immediate rust. I therefore obviate the necessity of soldering the joint between the united sheets. Furthermore, in the use of solder to effect a firm joint there is more or less danger of leakage at the joint because of climatic conditions contracting and expanding the metal. When the sheets contract and expand it has such action on the solder as to crack it with the result that the joint becomes defective and leaks. In my invention, I not only eliminate the solder and possibility of exposing the iron by reason of the coating becoming disturbed and removed, but I provide a firm substantial joint possessing such characteristics as to permit of contraction and expansion incident to atmospheric conditions without danger of causing leakage at the joints between the connected or united sheets.

What is claimed is:

1. A machine of the character described, including in combination, means for shearing and edging opposite ends of sheet material, means for transferring each sheet after it is sheared and edged into overlapping relation with a sheared and edged sheet, means operable upon the overlapped portions of the sheets to complete a single lock seam connection between the overlapping sheets, means for doubling the material at its single lock seam, means for flattening and double lock seaming the doubled material at the single lock seam, and means for feeding the material through the machine and winding it into a roll.

2. A machine of the character described, including in combination, means for automatically shearing and edging opposite ends of sheet material, automatic means for transferring each sheet after it is sheared

- and edged into overlapping relation with a sheared and edged sheet, means operable automatically upon the overlapped portions of the sheet to complete a single lock seam 5 connection between the overlapped sheets, means operable automatically for doubling the material at its single lock seam, automatic means for flattening the doubled material at the single lock seam to convert the 10 single lock seam into a double lock seam, means for automatically feeding the material through the machine and operating to wind the material into a roll subsequent to the single and double lock seam and doubling operations, and means whereby the rolled material may be discharged from the feeding and roll forming means.
3. A machine of the character described, including in combination, means for edging 20 ends of sheet material, means for placing the edged ends of the sheets of material in overlapping relation, means for feeding the overlapped sheets through the machine, means operating upon the sheets at their 25 overlapped portions to complete a single lock seam at the overlapping connection between said sheets, means operable on the material to double the same at the single lock seam, and means operable upon the single lock seam subsequent to the doubling of the latter to flatten out the doubled portion to provide a double lock seam at the joint between the sheets.
4. A machine of the character described, 35 including in combination, means for single lock seaming sheets together, comprising means for edging the ends of sheet material, means for placing the edged ends of the sheets of material in overlapping relation, means for feeding the overlapped sheets through the machine, means operating upon the sheets at their overlapped portions to complete a single lock seam at the overlapping connections between said sheets, 40 means for converting the single lock seam into a double lock seam comprising means operable upon the material at the single lock seam to double the material, means operable upon the single lock seam subsequent to the doubling of the latter to flatten out the doubled portion and complete a double lock seam at the joint between the sheets, and means for throwing out of operation the means which complete both the 45 single and the double lock seaming operations, and also the means which doubles the material, when a predetermined number of sheets have been double lock seamed.
5. A machine of the character described, 50 including in combination, means for placing edged sheets of material in overlapping relation, means for feeding the overlapped sheets through the machine, means operating upon the sheets at their overlapped portions to complete a single lock seam at the 55
- 60
- 65

overlapping connection between said sheets, means operable on the material to double the same at the single lock seam, and means operable upon the single lock seam subsequent to the doubling of the latter to flatten out the doubled portion and provide a double lock seam at the joint between the sheets, said feeding means operating to wind the united sheets into a roll, and means whereby the rolled sheets may be discharged from the combined feeding and winding means.

6. A machine of the character described including in combination, means for single lock seaming sheets of material comprising means for edging the ends of sheet material, 80 means for placing the sheets of material in overlapping relation, means for feeding the overlapped sheets through the machine, and means operating upon the sheets at their overlapped portions to complete a single lock seam at the overlapping connection between said sheets, means operable on the single lock seam to convert the same into a double lock seam comprising means operable on the material to double the same at 85 the single lock seam, and means operable upon the single lock seam subsequent to the doubling of the latter to flatten out the doubled portion to complete a double lock seam at the point between the sheets, means for 90 throwing out of operation the means which completes the single lock seam and also the means which completes the double lock seam, together with the means which doubles the material between the complete formation of 95 the single and double lock seams, the aforesaid means operating to form the united sheets into a roll, and means whereby the rolled sheets may be discharged from the combined feeding and roll forming means.

7. A machine of the character described, including in combination, means for edging opposite ends of sheet material, means for transferring each sheet after it is edged into overlapping relation with an edged sheet, means operable upon the overlapped portions of the sheets to complete a single lock seam connection between the overlapped sheets, means for doubling the material at the single lock seam, means for flattening the 110 doubled portion of the material to convert the single lock seam into a double lock seam, and means for feeding the material through the machine.

8. A machine of the character described, including in combination, means for edging opposite ends of sheet material, means for transferring each sheet after it is edged into overlapping relation with an edged sheet, means operable upon the overlapped portions of the sheets to complete a single lock seam connection between the overlapped sheets, means for doubling the material at the single lock seam, means for flattening the 115 doubled portion of the material to convert the single lock seam into a double lock seam, and means for feeding the material through the machine.

vert the single lock seam into a double lock seam, and means for feeding the material through the machine and winding the material into a roll.

5 9. A machine of the character described, including in combination, means for edging opposite ends of sheet material, means for transferring each sheet after it is edged into overlapping relation with an edged sheet, 10 means operable upon the overlapped portions of the sheets to complete a single lock seam connection between the overlapped sheets, means for doubling the material at the single lock seam, means for flattening 15 the doubled portion of the material to convert the single lock seam into a double lock seam, means for feeding the material through the machine and winding the material into a roll, and means operable to discharge the 20 rolled material from the feeding and winding means.

10. A machine of the character described, including in combination, means for edging sheet material, means for overlapping one 25 edged sheet with another edged sheet, means operable upon the overlapped portions of the sheets to complete a single lock seam connection between the overlapped sheets, means for doubling the material at the single 30 lock seam, means operable on the doubled material at the single lock seam to flatten out the same and form a double lock seam, and means for feeding the material through the machine.

35 11. A machine of the character described including in combination, means for single lock seaming sheets of material which comprises means for edging opposite ends of the sheet material, means for transferring each 40 edged sheet into overlapping relation with an edged sheet, and means operable upon the overlapped portions of the sheets to complete a single lock seam connection between the overlapped sheets, means for subsequently converting the single lock seam into a double lock seam which comprises means 45 for doubling the material at the single lock seam, means for flattening the doubled material at the single lock seam to complete a 50 double lock seam, means for feeding the material through the machine, and means for automatically throwing out of operation at predetermined times the means which completes the single lock seam and also the 55 means which completes the double lock seam, together with the means which doubles the material prior to completing the double lock seam.

60 12. A machine of the character described including in combination, means for single lock seaming sheets of material together which consists of means for edging opposite ends of sheet material, means for transferring each sheet after it is edged into overlapping relation with an edged sheet, and

means operable upon the overlapped portions of the sheets to complete a single lock seam connection between the overlapped sheets, means for converting the single lock seam into a double lock seam which consists 70 in means for doubling the material at the single lock seam, and means for flattening the doubled material at the single lock seam to complete a double lock seam, means for feeding the material through the machine 75 and winding the same into a roll, and means for automatically throwing out of operation at predetermined times the means which completes the single lock seam and also the means which completes the double lock seam. 80

13. A machine of the character described, including in combination, means for edging opposite ends of sheet material, means for transferring each sheet after it is edged into overlapping relation with the edged sheet, 85 means operable upon the overlapped portions of the sheets to complete a single lock seam connection between the overlapped sheets, means for converting the single lock seam into a double lock seam comprising 90 means for doubling the material at the single lock seam, and means for flattening the material at the single lock seam, means for feeding the material through the machine and winding it into a roll, means 95 operable to discharge the rolled material from the feeding and winding means, and means for throwing out of operation the means which completes the single lock seam, and also the means which completes the 100 double lock seam, together with the means which doubles the material prior to completing the double lock seam.

14. A machine of the character described, including in combination, means for single 105 lock seaming sheets of material comprising means for edging opposite ends of sheet material, means for overlapping one edged sheet with another edged sheet, means operable upon the overlapped sheets to complete 110 a single lock seam connection between the sheets, means for converting the single lock seam into a double lock seam, means for feeding the material through the machine, and means for throwing out of operation at predetermined times the means which completes the single lock seam and also the 115 means which converts the single lock seam into a double lock seam.

15. A machine of the character described, including in combination, means for feeding single lock seamed sheets through the machine, and means operable upon the sheets to convert the single lock seam into a 120 double lock seam. 125

16. A machine of the character described including in combination, means for feeding through the machine sheets which have been connected together by a single lock seam, means operable upon the sheets to 130

- double the seam at the single lock seam, and means operable upon the doubled portion to convert the single lock seam into a double lock seam.
17. A machine of the character described, including in combination, means for feeding through the machine sheets which have been connected together by a single lock seam, dies automatically operable to double the material at the single lock seam, and means operable automatically to flatten said doubled portion to convert the single lock seam into a double lock seam.
18. A machine of the character described including in combination, means for feeding through the machine sheets which have been connected together by a single lock seam, means operable upon the sheets to double the same at the single lock seam, and means operable upon the doubled portion to convert the single lock seam into a double lock seam, said feeding means also operating to wind the united sheets into a roll.
19. A machine of the character described including in combination, means for feeding through the machine sheets which have been connected together by a single lock seam, means operable upon the sheets to double the same at the single lock seam, means operable upon the doubled portion to convert the single lock seam into a double lock seam, said feeding means also operating to wind the united sheets into a roll, and means whereby the roll may be released from the combined feeding and winding means.
20. A machine of the character described, including in combination, means for feeding through the machine sheets which have been connected together by a single lock seam, dies automatically operable to double the material at the single lock seam, and means operable automatically to flatten said doubled portion to convert the single lock seam into a double lock seam, said feeding means also operating to form the united sheets into a marketable roll.
21. A machine of the character described, including in combination, means for feeding through the machine sheets which have been connected together by a single lock seam, dies automatically operable to double the material at the single lock seam, means operable automatically to flatten said doubled portion to convert the single lock seam into a double lock seam, said feeding means also operating to form the united sheets into a marketable roll, and levers operable to effect a release of the wound roll from the combined feeding and winding means.
22. A machine of the character described for operating upon a plurality of sheets which have been connected together by single lock seam joints comprising means for automatically doubling the material at the single lock seam joint, means for positioning said joints for said doubling operation and means operable automatically upon the doubled material to flatten the same against the body of the material and convert the single lock seam into a double lock seam.
23. A machine of the character described for operating upon a plurality of sheets which have been connected together by single lock seam joints comprising a vertically movable female die and a swinging male die operating to double the material at the single lock seam, and means subsequently operable on the doubled material to flatten the doubled material into the same plane with the body of the material and convert the single lock seam into a double lock seam.
24. The combination with means for converting a single lock seam connection between united sheets into a double lock seam comprising a male and a female die automatically operable to double the material at the single lock seam, means for positioning the single lock seams for said doubling operation, and means to operate automatically upon the doubled material at the single lock seam to force the doubled material into the same plane with the body of the material and convert the single lock seam into a double lock seam.
25. Means for converting a single lock seam connection between united sheets into a double lock seam comprising means to clamp the material, said means including a female die, a male die arranged for co-operation with the female die to draw upon one of the sheets to double the material at the single lock seam, and means operable upon the doubled portion of the material at the single lock seam to convert the latter into a double lock seam.
26. A machine of the character described, including in combination, means for edging opposite ends of sheet material, means for placing each sheet after it is edged into overlapping relation with another edged sheet, means operable upon the overlapped sheets at their point of overlapping to complete a single lock seam, means consisting of male and female dies for doubling the material at the single lock seam, means for subsequently operating upon the doubled portion of the material to convert the single lock seam into a double lock seam, and means for feeding the material through the machine.
27. A machine of the character described including in combination, means for shearing and edging opposite ends of sheet material, means for placing each sheet after it is sheared and edged into overlapping relation with a sheared and edged sheet, means operable upon the overlapped sheets at their point of overlapping to complete a single lock seam, means consisting of male and female dies for doubling the material at the

- single lock seam, means for subsequently operating upon the doubled portion of the material to convert the single lock seam into a double lock seam, means for feeding the material through the machine, means for automatically throwing the male and female dies into coöperative relation subsequent to the formation of the single lock seam and to throw the male and female dies out of coöperative relation prior to the completion of the double lock seam.
28. A machine of the character described including in combination means for single lock seaming sheets of material comprising means for edging opposite ends of sheet material, means for placing each sheet after it is edged into overlapping relation with an edged sheet, and means operable upon the overlapped sheets at their point of overlapping to complete a single lock seam, means for converting the single lock seam into a double lock seam comprising male and female dies to double the material at the single lock seam, and means for subsequently operating upon the doubled portion of the material to complete the double lock seam, means for feeding the material through the machine, means for automatically throwing the male and female dies into coöperative relation subsequent to the formation of the single lock seam and to throw the male and female dies out of coöperative relation prior to the complete formation of the double lock seam, and means operable to throw the means which completes the single and also the means which completes the double lock seam out of operation when a predetermined number of sheets have been double lock seamed.
- 40 29. A machine of the character described including in combination, means for single lock seaming sheets of material comprising means for edging opposite ends of sheet material, means for placing one edged sheet into overlapping relation with another edged sheet, means for feeding the overlapped sheets through the machine, and means operable upon the overlapped portions of the sheets to complete a single lock seam connection between the sheets, means to convert the single lock seam into a double lock seam comprising means for doubling the material at the single lock seam, and means operable upon the doubled portion to complete the double lock seam, said feeding means being operable to wind the united sheets into a roll, means for throwing the means which completes the single lock seam and also the means which completes the double lock seam out of operation when a predetermined number of sheets have been double lock seamed, and means to effect a discharge of the roller material from the feeding and roll forming means whereby a separation between the last of the predetermined number of sheets to be united and the following overlapped sheets is effected so that said following sheets may be connected to the combined feeding and roll forming means to repeat the aforesaid operations.
30. A machine of the character described, including in combination, means for edging opposite ends of sheet material, means for transferring each sheet after it is edged into overlapping relation with another edged sheet, means operable upon the overlapped portions of the sheets to complete a single lock seam connection between the sheets at their overlapped points, means operable upon the material at the single lock seam to dispose the single lock seam at an angle to the plane of the material, means subsequently operable upon the material at the single lock seam to convert the latter into a double lock seam, and means for feeding the material through the machine and winding it into a roll.
31. A machine of the character described, including in combination, means for feeding through the machine sheets which have been connected together by a single lock seam, means operable upon the material at the single lock seam to dispose the seam at an angle to the plane of the material, and means subsequently operable automatically to operate upon the angularly disposed single lock seam to convert the latter into a double lock seam.
32. Means for converting a single lock seam connection between united sheets into a double lock seam, comprising means to feed the united sheets into the machine, a vertically movable die plate having a recess therein provided with a straight flat wall, and a swinging die having a portion adapted to force the single lock seam into said recess and against said straight flat face of the recess to dispose the single lock seam at an angle with relation to the body of the sheets and means to automatically operate said dies.
33. Means for converting a single lock seam connection between united sheets into a double lock seam, comprising means to feed the united sheets into the machine, a vertically movable die plate having a recess therein provided with a straight flat wall, and a swinging die having a portion adapted to force the single lock seam into said recess and against said straight flat face of the recess to dispose the single lock seam at an angle with relation to the body of the sheets, and means subsequently automatically operable upon the single lock seam to force the latter into the same plane with the body of the sheets and thereby convert the single lock seam into a double lock seam.
34. Means for converting a single lock seam connection between united sheets into

a double lock seam, comprising means to feed the united sheets into the machine, means operable upon the sheets at the single lock seam to deflect the latter into a plane at an angle to the plane of the body of the sheets, and means subsequently operable automatically upon the angularly disposed single lock seam to force it into a plane parallel with the united sheets and thereby convert 10 the single lock seam into a double lock seam.

35. A machine of the character described, including in combination, means for shearing and edging opposite ends of sheet material, means for transferring each sheet 15 after it is sheared and edged into overlapping relation with another sheared and edged sheet, means operable upon the overlapped portions of the sheets to complete a single lock seam connection between the 20 overlapped sheets, means operable to double the material at its single lock seam, means for flattening the doubled material at the single lock seam to convert the single lock seam into a double lock seam, and 25 means for feeding the material through the machine.

36. A machine of the character described, including in combination, a frame, means for edging opposite ends of the sheet material 30 means for transferring each sheet after it is edged into overlapping relation with another edged sheet, rollers operable upon the overlapped sheets to complete a single lock seam connection between the sheets, a 35 gear connection between said rollers, a drive shaft journaled in said frame, a driving connection between said shaft and one of the aforesaid rollers, an operative connection 40 between the edging means and one of said rollers, an operative connection between the transferring means and the drive shaft, means operable automatically to dispose the 45 single lock seam at an angle to the plane of the sheet material, a second set of rollers operable upon the material to force the angularly disposed single seam parallel with the sheets to convert the single lock seam into a double lock seam, a driving connection 50 between the drive shaft and one of said second set of rollers, a gear connection between the second set of rollers, and means operatively 55 connected with the main drive shaft to automatically feed the material through the machine.

55. 37. A machine of the character described, including in combination, a frame, means for edging opposite ends of the sheet material, means for transferring each sheet after it is edged into overlapping relation with 60 another edged sheet, rollers operable upon the overlapped sheets to complete a single lock seam connection between the sheets, a gear connection between said rollers, a drive shaft journaled in said frame, a driving connection 65 between said shaft and one of the

aforesaid rollers, an operative connection between the edging means and one of said rollers, an operative connection between the drive shaft and the transferring means, means operable automatically to dispose the 70 single lock seam at an angle to the plane of the sheet material, a second set of rollers operable upon the material to force the angularly disposed single seam parallel with the sheets to convert the single lock seam 75 into a double lock seam, a driving connection between the drive shaft and one of said second set of rollers, a gear connection between the second set of rollers, means operatively connected with the main drive shaft 80 to automatically feed the material through the machine, and means for automatically throwing said sets of rollers out of operative relation at predetermined times.

38. A machine of the character described, including in combination, a frame, means for edging opposite ends of the sheet material, means for transferring each sheet after it is edged into overlapping relation with another edged sheet, rollers operable upon the overlapped sheets to complete a single lock seam connection between the sheets at their points of overlapping, a gear connection between said rollers, a drive shaft journaled in said frame, a driving connection 95 between said shaft and one of the aforesaid rollers, an operative connection between the edging means and one of said rollers, an operative connection between the drive shaft and the transferring means, means 100 operable automatically to dispose the single lock seam at an angle to the plane of the sheet material, a second set of rollers operable upon the material to force the angularly disposed single seam parallel with the 105 sheets to convert the single lock seam into a double lock seam, a driving connection between the drive shaft and one of said second set of rollers, a gear connection between the second set of rollers, and means operatively 110 connected with the main drive shaft to automatically feed the material through the machine, said feeding means also winding the material into a marketable roll.

39. A machine of the character described, including in combination, a frame, means for edging opposite ends of the sheet material, means for transferring each sheet after it is edged into overlapping relation with another edged sheet, rollers operable upon 115 the overlapped sheets to complete a single lock seam connection between the sheets at their points of overlapping, a gear connection between said rollers, a drive shaft journaled in said frame, a driving connection 120 between said shaft and one of the aforesaid rollers, an operative connection between the edging means and one of said rollers, an operative connection between the drive shaft 125 and transferring means, means operable 130

automatically to dispose the single lock seam at an angle to the plane of the sheet material, a second set of rollers operable upon the material to force the angularly disposed single seam parallel with the sheets to convert the single lock seam into a double lock seam, a driving connection between the drive shaft and one of said second set of rollers, a gear connection between the second set of rollers, and means operatively connected with the main drive shaft to automatically feed the material through the machine, said feeding means also winding the material into a marketable roll, and means whereby the rolled material on the combined feeding and winding means may be discharged therefrom.

40. A machine of the character described, including in combination, a frame, means for edging opposite ends of the sheet material, means for transferring each sheet after it is edged into overlapping relation with another edged sheet, rollers operable upon the overlapped sheets to operate upon the overlapped portions of the sheets to complete a single lock seam connection between the sheets, a gear connection between said rollers, a drive shaft journaled in said frame, a driving connection between said shaft and one of the aforesaid rollers, an operative connection between the edging means and one of said rollers, an operative connection between the drive shaft and the transferring means, means operable automatically to dispose the single lock seam at an angle to the plane of the sheet material, a second set of rollers operable upon the material to force the angularly disposed single seam parallel with the sheets to convert the single lock seam into a double lock seam, a driving connection between the drive shaft and one of said second set of rollers, a gear connection between the second set of rollers, means operatively connected with the main drive shaft to automatically feed the material through the machine, means for automatically throwing said sets of rollers out of operative relation at predetermined times, said feeding means also winding the material into a roll, and means whereby the roll of material may be discharged from said feeding and winding means.

41. A machine of the character described, including in combination, means for edging opposite ends of sheet material, means for placing each sheet after it is edged into overlapping relation with another edged sheet, means operable upon the overlapped sheets at their point of overlapping to complete a single lock seam, means operable upon the single lock seam to double the sheet material at the single lock seam, means operable upon the doubled portion at the single lock seam to convert the latter

into a double lock seam, means for feeding the material through the machine and to wind it into a roll, and means operable to prevent the completion of single and double lock seams when a predetermined number of sheets have been wound into a roll and thereby indicate that a predetermined number of sheets have been double lock seamed.

42. A machine of the character described including in combination, means for edging opposite ends of sheet material, means for placing each sheet after it is edged into overlapping relation with another edged sheet, and means operable upon the overlapped sheets to complete a single lock seam, means for subsequently converting the single lock seam into a double lock seam comprising means operable to double the sheet material at the single lock seam; and means operable upon the doubled portion at the single lock seam to complete a double lock seam, means for feeding the material through the machine and to wind it into a roll, and means for throwing out of operation the means which completes the single lock seam and also the means which completes the double lock seam when a predetermined number of sheets have been double lock seamed and wound into a roll, and thereby indicate that the predetermined number of sheets have been double lock seamed.

43. A machine of the character described, including in combination, means for edging opposite ends of sheet material, means for transferring each sheet after it is edged into overlapping relation with another edged sheet, a set of rollers operable upon the overlapped portions of the sheets to complete a single lock seam connection between the overlapped sheets, means for disposing the single lock seam at an angle to the plane of the sheet, a set of rollers operable to flatten the angularly disposed single seam into parallel relation with the sheets to convert the single lock seam into a double lock seam, means for feeding the material through the machine, and means for throwing said sets of rollers out of operative relation at predetermined times.

44. A machine of the character described including in combination, means for edging opposite ends of sheet material, means for transferring each sheet after it is edged into overlapping relation with another edged sheet, upper and lower rollers operable upon the overlapped portion of the sheets to complete a single lock seam at the overlapped connection between the sheets, means for doubling the material at its single lock seam, upper and lower rollers operable to flatten the doubled material at the single lock seam to convert the latter into a double lock seam, means for feeding the material through the machine, and means operable automatically

to lift the upper rollers out of operative relation with the corresponding lower rollers.

45. A machine of the character described, including in combination, means for edging opposite ends of sheet material, means for transferring each sheet after it is edged into overlapping relation with another edged sheet, upper and lower rollers operable upon the overlapped portion of the sheets to complete a single lock seam at the overlapped connection between the sheets, means for doubling the material at its single lock seam, upper and lower rollers operable to flatten the doubled material at the single lock seam 10
15 to convert the latter into a double lock seam, means for feeding the material through the machine, and means operable automatically to lift the upper rollers out of operative relation with the corresponding lower rollers 20 and simultaneously throw said doubling means out of operation.

46. A machine of the character described including in combination, means for edging opposite ends of sheet material, means for transferring each sheet after it is edged into overlapping relation with another edged sheet, upper and lower rollers operative upon the overlapped portions of the sheets to complete a single lock seam connection 25
30 between the overlapped sheets, means for doubling the material at its single lock seam, upper and lower rollers for operation upon the doubled portion of the material to convert the single lock seam into a double lock seam, means for feeding the material through the machine, and means to indicate step by step the formation of each double lock seam.

47. A machine of the character described including in combination, means for edging opposite ends of sheet material, means for transferring each sheet after it is edged into overlapping relation with another edged sheet, upper and lower rollers operable upon 40
45 the overlapped portions of the sheets to complete a single lock seam connection between the overlapped sheets, means for doubling the material at its single lock seam, upper and lower rollers for operation upon the doubled portion of the material to convert the single lock seam into a double lock seam, means for feeding the material through the machine, and means to indicate step by step the formation of each double lock seam and 50
55 for simultaneously throwing said rollers out of operation when a predetermined number of sheets have been double lock seamed.

48. A machine of the character described, including in combination, means for edging opposite ends of sheet material, means for transferring each sheet after it is edged into overlapping relation with another edged sheet, rollers operable upon the overlapped portions of the sheets to complete a single 60
65 lock seam connection between said sheets,

means for doubling the material at the single lock seam, rollers operable upon the doubled portion to convert the single lock seam into a double lock seam, means for feeding the material through the machine 70 and winding it into a roll, levers connected to one of the first-named rollers, levers connected to one of the second-mentioned rollers, connections between said levers, and means operable automatically to shift said 75 levers and throw the first and second-mentioned rollers out of operation when a predetermined number of sheets have been double lock seamed.

49. A machine of the character described 80 including in combination, means for single lock seaming sheets of material comprising means for edging opposite ends of sheet material, means for transferring each edged sheet into overlapping relation with another edged sheet, rollers operable upon the overlapped portions of the sheets to compress the material and thereby complete a single lock seam connection between said overlapped sheets, means for converting the 85 single lock seam into a double lock seam comprising means for doubling the material at the single lock seam, rollers operable upon the doubled portion to compress the latter and thereby convert the single lock seam 90 into a double lock seam, means for feeding the material through the machine, and winding it into a roll, levers connected to one of the first-named rollers, levers connected to one of the second mentioned rollers, connections between said levers, and a ratchet mechanism to indicate step by step the number of double lock seams formed in the material, and means operating in conjunction 95 with the aforesaid levers to operate the latter and thereby throw both sets of compressing 100 rollers out of operation.

50. A machine of the character described including in combination, means for single lock seaming sheets of material, comprising 110 means for edging opposite ends of sheet material, means for transferring each sheet after it is edged into overlapping relation with another edged sheet, rollers for compressing the sheets at their points of overlapping to complete a single lock seam at the connection between the sheets, means for converting the single lock seam into a double lock seam comprising means for doubling the material at the single lock seam and 115 rollers operable upon the doubled portion to compress the same and thereby complete the formation of the double lock seam, means for feeding the material through the machine and winding it into a roll, levers connected to one of the first mentioned rollers, levers connected to one of the second mentioned rollers, connections between said levers, a ratchet mechanism to indicate step 120 by step the number of double lock seams 125 130

formed in the material, and means operating to actuate said levers to throw both sets of rollers out of operation together with said doubling means.

5 51. A machine of the character described including in combination, means for simultaneously edging both ends of the sheet material, means for transferring each sheet after it is edged into overlapping relation 10 with an edged sheet, and means to firmly unite the overlapped sheets together.

52. A machine of the character described, including in combination, means for edging the sheet material, means for transferring 15 each sheet after it is edged into overlapping relation with an edged sheet, means for operating upon the sheets at their overlapping portions to complete a lock seam joint connection between the sheets, and 20 means for automatically throwing the seam completing means out of operation.

53. A machine of the character described, including in combination, means for edging ends of sheet material, means subsequently 25 automatically operable upon the edged ends of the sheets to complete a single lock seam connection between the sheets, means automatically operable upon the single lock seam to deflect the same, and means automatically 30 operable subsequently to act upon the deflected single lock seam to convert it into a double lock seam.

54. A machine of the character described including in combination, means for edging 35 ends of sheet material, means for transferring edged sheets into overlapping relation, means automatically operable upon the overlapped edged sheets to complete a single lock seam joint connection between the 40 sheets, means automatically operable upon the single lock seam to deflect the same, means automatically operable to subsequently act upon the deflected single lock seam to complete the formation of a double 45 lock seam, and means for simultaneously throwing out of operation the means which completes the single lock seam and also the means which completes the double lock seam together with the means which deflects the 50 single lock seam.

55. A machine of the character described, including in combination, means for edging ends of sheet material, means subsequently 55 automatically operating upon the edged ends of adjacent sheets to complete a single lock seam joint connection between the adjacent sheets, means automatically operable upon the single lock seam to deflect the same, and means automatically operable to subsequently act upon the deflected single lock seam to convert it into a double lock seam, and means for indicating the number of 60 double lock seams formed.

56. A machine of the character described, 65 including in combination, means for single

lock seaming the edged sheets together, means operable automatically to deflect the material at the single lock seam, means subsequently operable to convert the single lock seam into a double lock seam, means for 70 feeding the material through the machine, and means whereby a given number of seamed sheets are wound into a roll, and means whereby the roll may be discharged from the machine. 75

57. In a machine of the character described, including in combination, means including compressing elements for connecting sheets of material together, and means to indicate the number of connections effected and to throw the compressing elements out of operation when a predetermined number of sheets have been connected together. 80

58. A machine of the character described including in combination, means including compressing elements for connecting sheets of material together, and means operatively connected with the connecting means to throw the compressing elements of the connecting means out of operation when a predetermined number of sheets have been connected together. 85

59. A machine of the character described including in combination means for forming 90 single lock seam connections between sheets of material comprising means for edging the ends of sheet material, means for compressing the edged ends of sheets at their points of overlapping to complete a single 95 lock seam connection between the sheets, means for subsequently converting the single lock seam into a double lock seam which comprises means to deflect the material at the single lock seam, means automatically 100 operable to act upon the deflected single lock seam to complete a double lock seam, and means operatively connected to the means which completes the single lock seam and also to the means which completes the 105 double lock seam to throw out of operation the means which completes the single lock seam and also the means which forms the double lock seam when a predetermined number of sheets have been double lock 110 seamed. 115

60. A machine of the character described, including in combination, means for seaming sheets of material together, including compressing elements, means for feeding the 120 sheet material through the machine, and means independent of the feeding means operable to throw out of operation the compressing elements of the seaming means when a predetermined number of sheets have 125 been connected together.

61. A machine of the character described including in combination, means for double lock seaming sheets of material together, and means for indicating the number of 130

sheets double lock seamed and to discontinue double lock seaming of the sheets when a predetermined number of sheets have been double lock seamed.

5. 62. A machine of the character described including in combination, means for edging ends of sheet material, means subsequently automatically operable upon the edged ends of the sheets to complete a single lock seam 10 connection between the sheets, means automatically operable upon a single lock seam to convert the latter into a double lock seam comprising means to deflect the single lock seam, and means automatically operable 15 upon the deflected single lock seam to complete a double lock seam, means to indicate the number of double lock seams formed and to throw out of operation the means which completes the single lock seams and also the 20 means which completes the double lock seams when a predetermined number of sheets have been double lock seamed.
63. A machine of the character described including in combination, means for edging 25 ends of sheet material, means subsequently automatically operable upon the edged ends of the sheets to complete a single lock seam connection between the sheets, means automatically operable upon a single lock seam 30 to convert the latter into a double lock seam comprising means to deflect the single lock seam, and means automatically operable upon the deflected single lock seam to complete a double lock seam, and means to indicate the number of double lock seams 35 formed.

64. A machine of the character described including in combination, means for connecting sheets of material together and 40 means to automatically indicate and regulate the number of connections made between the sheets.

65. In a machine for operating upon a continuous sheet of roofing material composed of a plurality of overlapped edged sheets, means to feed the material into the machine, automatic means for doubling each sheet of material at the point of overlapping, and automatic means operable upon 45 the doubled material to force the same into a plane parallel with the plane of the remainder of the material.

66. In a machine for operating upon sheet roofing material composed of a plurality of 55 overlapping edged sheets, means for feeding the material into the machine, and means operative on the material to bend and fold the same at the point of overlapping to form a double lock seam connection between the 60 sheets.

67. In a machine for operating upon sheet roofing material composed of a plurality of overlapping edged sheets, means for feeding the material into the machine, and means

operative to bend and fold the material at 65 the point of overlapping to form a watertight double lock seam connection between the sheets.

68. A machine of the character described, including in combination, means for feeding 70 single lock seamed sheets through the machine, means for operating upon the material upon opposite sides of the single locked seam to deflect the seamed ends alike and dispose them one upon the other at an 75 angle to the plane of the body of the sheets, and means subsequently operable to force the angularly disposed single locked seam into a plane parallel to the body of the material and thereby form a double locked seam 80 connection between the sheets.

69. A machine of the character described, including in combination, means whereby sheets of material may be joined end to end, means for operating automatically upon the 85 sheets on opposite sides of the joined connection to fold the sheets alike at their joined ends, and dispose the joined ends and the fold between the sheets, and automatic means to compress the folded ends together 90 in a plane parallel with the remainder of the material and thereby double lock seam the sheets together.

70. A machine of the character described including in combination means for bending 95 and shearing opposite ends of sheet material to edge the same, means for transferring each sheet after it is sheared and bent into overlapping relation with an edged sheet, and means operable upon the overlapped 100 sheets to effect a permanent connection between the same.

71. A machine of the character described including in combination means for bending and shearing opposite ends of sheet material 105 to edge the same, means for transferring each sheet after it is sheared and bent into overlapping relation with an edged sheet, means operable upon the overlapped sheets to effect a permanent connection between 110 the same, and means for indicating the number of permanent connections effected.

72. A machine of the character described including in combination means for bending and shearing opposite ends of sheet material 115 to edge the same, means for transferring each sheet after it is sheared and bent into overlapping relation with an edged sheet, means operable upon the overlapped sheets to effect a permanent connection between 120 the same, and means for indicating the number of permanent connections effected and to throw out of operation the means for effecting the permanent connections when a predetermined number of connections 125 have been made.

73. A machine of the character described including in combination, means for clamp-

ing opposite ends of sheet material with the ends of the material projecting beyond the clamping means, means engageable with the projecting ends of the material to bend the 5 projecting ends into engagement with the clamping means to edge each end of the sheets, means to shear the edges of the projecting ends of the material when bending the same, means for overlapping one edged 10 sheet with another edged sheet, and means for permanently connecting the overlapped sheets together.

74. A machine of the character described comprising means for clamping opposite 15 ends of sheet material with the ends of the material projecting beyond the clamping means, means engageable with the projecting ends of the material to bend the projecting ends into engagement with the 20 clamping means to edge each end of the sheets, means to shear the edges of the projecting ends of the material when bending the same, and means for overlapping one edged sheet with another edged sheet.

25 75. A machine of the character described including in combination, means for edging sheet material, means for placing the edged sheets in overlapping relation, means for feeding the overlapped sheets through the 30 machine, and means operable directly upon the sheets to bend the same at their points of overlapping to effect a permanent connection between the sheets.

76. A machine of the character described 35 including in combination, means for edging sheet material, means for placing the edged sheets in overlapping relation, means for feeding the overlapped sheets through the machine, and means operable upon the 40 sheets at their points of overlapping to effect a permanent connection between the sheets, said feeding means winding the permanently connected sheets into a roll.

77. A machine of the character described 45 including in combination, means for edging sheet material, means for placing the edged sheets in overlapping relation, means for feeding the overlapped sheets through the machine, and means operable upon the 50 sheets at their points of overlapping to effect a permanent connection between the sheets, said feeding means winding the permanently connected sheets into a roll, and means whereby the rolled material may be 55 discharged from the combined feeding and winding means.

78. A machine of the character described including in combination, means for clamping sheet material adjacent its ends to hold 60 the same firmly with the sheet material projecting at its ends beyond the clamping means, means engageable with the projecting ends of the material to bend and shear the same, means to transfer a bent and

sheared sheet of material from the clamping 65 means into overlapping relation with a sheared and bent sheet of material, and means operable upon the overlapped sheets to effect a permanent connection between the same. 70

79. A machine of the character described including in combination, means for clamping sheet material adjacent its ends to hold the same firmly with the sheet material projecting at its ends beyond the clamping 75 means, means engageable with the projecting ends of the material to bend and shear the same, means to transfer a bent and sheared sheet of material from the clamping means into overlapping relation with a 80 sheared and bent sheet of material, means operable upon the overlapped sheets to effect a permanent connection between the same, means to deflect the material at the connected ends of the sheet material to dispose the same at an angle to the body of the material, and means subsequently operable upon the angularly disposed portion to compress the same into the plane of the body 85 portion of the connected sheets. 90

80. The combination with means to hold sheet material in fixed position, of means to automatically engage each end of the fixed sheet and bend the same, one end in a direction opposite to the direction of bend of the 95 other end of the sheet material, means for positioning one edged sheet into overlapping relation with another edged sheet, and means for manipulating the sheets at their points of overlapping to form a water-tight 100 double lock seam.

81. In a machine for operating upon roofing material, means for joining a plurality of sheets together end to end, automatic means for doubling each sheet at the point 105 of connection between it and the adjacent sheet joined thereto, and automatic means operable upon the doubled material to force the same into a plane parallel with the plane of the body of the material. 110

82. In a machine for operating upon sheet roofing material, means for automatically joining a plurality of sheets together end to end to form a single lock seam, and means for automatically double lock seaming the 115 sheets together at the single lock seam joint connection comprising means for doubling the material at the single lock seam and means operable upon the doubled portion to force the same into a plane parallel with the 120 plane of the remainder of the material.

83. A machine of the character described including in combination means for feeding single lock seamed sheets through the machine, means operating upon the material 125 upon opposite sides only of the single lock seam to deflect the single lock seam at an angle to the plane of the body of the sheets,

and means subsequently operable to force the angularly disposed single lock seam into a plane parallel to the plane of the body of the sheets and thereby form a double lock seam connection between the sheets.

84. A machine of the character described including in combination, means whereby sheets of material may be joined together at their ends, means for operating automatically upon the sheets on opposite sides only of the overlapped portions thereof to double the material at the point of overlapping, and automatic means operable upon the doubled material to force the same into a plane parallel with the remainder of the material and thereby connect the sheets firmly together.

85. A machine of the character described including in combination means for automatically completing a single lock seam at the meeting edges of hooked, overlapped sheets, means for subsequently pulling one sheet over the other and creasing both sheets at the sides only of said completed single lock seam, and means for automatically forcing the single lock seam into a plane parallel with the body of the sheets and thereby forming a double lock seam connection between the sheets.

86. A machine of the character described including in combination, means for feeding single lock seamed sheets through the machine, means operable upon the sheets at opposite sides of the single lock seam to deflect the latter at an angle to the plane of the body of the sheets, and means subsequently operable to force the angularly disposed single lock seam into a plane parallel with the plane of the body of the material and thereby convert the single lock seam into a double lock seam.

87. In a machine of the character described, means for automatically completing a single lock seam at the meeting edges of hooked overlapped sheets, means for automatically operating upon the sheet material at opposite sides of the single lock seam to pull one sheet toward the other with the seam disposed at an angle between the sheets, and means for forcing the sheets and the single lock seam into substantially parallel planes to thereby form a double lock seam connection between the sheets.

88. In a machine for operating upon a continuous sheet of roofing material composed of a plurality of overlapped edged sheets, means for feeding the sheets into the machine and automatic means operable to manipulate adjacent ends of the sheets at the point of overlapping to bend and fold the material and subsequently force the same into a plane parallel with the plane of the remainder of the material.

89. In a machine for operating upon sheet roofing material composed of a plurality of overlapped edged sheets, means for feeding

the material through the machine and automatic means for bending and folding each sheet alike and in the same proportion at the point of overlapping so as to form a double lock seam connection between the sheets.

70

90. In a machine for operating upon a continuous sheet of roofing material composed of a plurality of overlapped edged sheets, means for feeding the material into the machine, means to automatically operate upon the sheets at the point of overlapping to fold the end of each sheet alike one about the other, and means to compress the folded overlapped portions into a plane parallel with the remainder of the material.

75

91. In a machine for operating upon sheet roofing material composed of a plurality of overlapped edged sheets, means for feeding the material through the machine, means for intermittently arresting operation of the feeding means, and means for bending the material at the points of overlapping at the intervals of rest of said feeding means.

80

92. In a machine of the character described, the combination with means for moving loosely hooked-together sheets forward, of means for pressing in succession a number of the loosely-engaged hooks to lock them until a predetermined number of hooks have been locked and means for rendering the pressing means inoperative at predetermined intervals to permit the next loosely-engaged hooks to pass the pressing means and remain in a loose condition.

95

93. In a machine of the character described, the combination with means for forming a hook on one edge of each sheet, of means for forming a hook on another edge of each sheet; means for loosely engaging a hook of one sheet with the hook of another sheet, means for moving the loosely-engaged sheets forward, means for pressing in succession a number of the loosely engaged hooks to lock them until a predetermined number of hooks have been locked, and means for rendering the pressing means inoperative to permit the next pair of loosely-engaged hooks to pass the pressing means and remain in a loose condition.

100

94. In a machine for operating upon sheet roofing material composed of a plurality of overlapping edged sheets, means for feeding the material into the machine, means for intermittently arresting operation of the feeding means, means for doubling the material at the point of overlapping and forcing the doubled portion into a plane substantially parallel with the plane of the remainder of the material.

110

95. In a machine for operating upon sheet roofing material composed of a plurality of edged sheets, means for feeding the material into the machine, means actuated by the material to arrest operation

130

- of the feeding means, and means to bend the material at the point of overlapping.
96. In a machine for operating upon sheet roofing material composed of a plurality of connected sheets, means to bend the material at the points of connection to form a water tight double lock seam connection between the sheets and means to position the connections for the bending operations.
97. In a machine for operating upon sheet roofing material composed of a plurality of sheets which have been single lock seamed together, means for feeding the material into the machine, means for intermittently arresting operation of the feeding means, and means for converting the single lock seams into double lock seams at the intervals of rest of said feeding means.
98. In a machine for operating upon sheet roofing material composed of a plurality of overlapping edged sheets, means for feeding the material into the machine, and means actuated by the material to arrest operation of the feeding means.
99. In a machine for operating upon sheet roofing material, means for edging the sheets, means for positioning an edged sheet in overlapping relation with another edged sheet, means for feeding the overlapped sheets into the machine, means operating on the overlapped portions of the sheets to complete a seam, and devices subsequently operable on the sheets at the point of overlapping to convert the single seam into a double seam.
100. In a machine for operating upon sheet roofing material composed of a plurality of sheets which have been single lock seamed together, means for feeding the material through the machine, including a reel upon which the material is wound, means for intermittently arresting operation of the feeding means, means for converting the single lock seams into double lock seams at the intervals of rest of said feeding means, and means for indicating when a predetermined number of sheets have been double lock seamed.
101. In a machine for operating upon sheet roofing material composed of a plurality of overlapping edged sheets, a reel for feeding the material through the machine, means for operating the reel, and means to bend and fold the material at the points of overlapping to form a double lock seam.

In testimony whereof I affix my signature in presence of two witnesses.

EDWARD W. SALMON, Jr.
